PORTRABLE BUILDING

Floyd E. Bigelow, Jr., P.O. Box 7064, Houston, Tex.
Filed Aug. 21, 1959, Ser. No. 835,211
4 Claims. (Cl. 20—2)

This invention relates to a portable building, and more particularly to a building structure which may be disassembled and formed into a compact package for transportation and which is easily assembled and erected.

The invention has for an important object the provision of a building which is made up of unitary walls, a floor or base unit and a unitary roof structure, the walls being adapted to be placed one upon another on the floor, and the roof and floor being constructed to enclose the walls to form a unitary package.

Another object of the invention is to provide a building having detachable walls floor and roof, and which is capable of use as a separate unit or which may be combined with other such units to form a multi-unit structure.

A further object of the invention is to provide a building of unitary design having detachable walls, floor and roof, and embodying means for assembling and connecting together a number of such buildings to form a structure of larger size.

Another object of the invention is the provision of a joint structure for buildings of the type having detachable walls, floor and roof, whereby several such buildings may be connected together in end to end or side by side relation with the facing, adjacent walls removed to form a unitary structure of larger size.

A further object of the invention is to provide a weather tight, detachable joint structure for portable buildings of the type having detachable walls, floor and roof whereby a number of such buildings may be connected together to form a structure of larger dimensions.

Another object of the invention is the provision of a joint structure for connecting together buildings of the type having detachable walls and a detachable roof of inverted tray shape adapted to be placed over the upper edges of the walls with the side portions of the roof extending downwardly exteriorly of the upper margins of the walls, which joint structure embodies an elongated member of channel shape, adapted to be placed in an upwardly opening position between the roofs of two such buildings placed in side by side relation, with the facing, adjacent walls of the building removed and the adjacent side portions of the roofs extending downwardly inside of the sides of the channel to form a water shedding, trough like connection between the roofs.

A further object of the invention is to provide a joint structure for use in connecting together buildings of the type having detachable walls and a detachable roof of inverted tray like shape, which joint structure embodies an elongated member of channel shape whose sides are adapted to be inserted beneath the adjacent downwardly extending side portions of the roofs of two such buildings placed in side by side or end to end relation with the facing adjacent walls removed to form an upwardly opening trough between the roofs, and side members adapted to be placed between adjacent walls of the buildings in overlapping relation thereto, said channel having end portions disposed exteriorly of and in overlapping relation to said adjacent walls and the upper end portions of said side members.

Another object of the invention is the provision of a joint structure for connecting together buildings of the type mentioned which is easily applied and removed and which forms a strong and weather tight connection.

The above and other important objects and advantages of the invention may best be understood from the following

2

detailed description, constituting a specification of the same, when considered in conjunction with the annexed drawings, wherein—

FIGURE 1 is a perspective view of a preferred embodiment of the invention showing the manner in which the unitary buildings are connected together by the detachable joint structure of the invention;

FIGURE 2 is a fragmentary, perspective view, on a somewhat enlarged scale, showing details of the structure 5 of the detachable joint and the manner in which the same is applied in connecting together the buildings of the invention;

FIGURE 3 is a cross-sectional view taken along the line 10 3—3 of FIGURE 2, looking in the direction indicated by the arrows;

FIGURE 4 is a fragmentary side view on a somewhat enlarged scale of the detachable joint structure of the invention.

FIGURE 5 is a fragmentary cross-sectional view, on an 20 enlarged scale, showing structural details of the upper portion of the detachable joint of the invention and the internal structures of the roofs of the buildings connected thereby; and

FIGURE 6 is a fragmentary perspective view, on an 25 enlarged scale showing end portions of the channel member and side member of the joint of the invention and the manner in which the members are shaped for cooperation in assembling the joint.

Referring now to the drawings in greater detail, the 30 invention is disclosed herein in connection with portable buildings of the type having detachable side and end walls 10 and 12, which may be assembled with a floor or base 14, preferably of rectangular shape, and a detachable roof 16 which is of, inverted tray shape having side 35 portions 18 which are adapted to be positioned exteriorly of the upper marginal portions of the walls when the building is assembled.

The portable building of the invention is preferably 40 constructed to permit the walls 10 and 12 to be detached from the floor or base 14 and laid one upon another on top of the floor, and the roof 16 is constructed so that the side portions 18 thereof will surround the walls to enclose the same, so that the roof and floor may serve to form a box in which the remaining parts of the building will be enclosed for transportation as a complete unit to be assembled at any desired location.

The walls 10 and 12 are preferably of unitary construction, dimensioned to fit within the tray like roof when detached, and to permit the roof to be placed over the 50 upper edges of the walls when the walls are erected, with the sides of the roof disposed exteriorly of the walls to hold the walls against spreading apart and to form a weather tight structure. The floor or base 14 is constructed and dimensioned to allow the walls to be placed in superposed relation thereon when the walls are detached and to form the bottom of the box-like enclosure of which the roof forms the sides and top when the building is dismantled and formed into a compact assemblage.

The walls 10 and 12 may be grooved or otherwise interfitting or provided with suitable means such as vertically disposed angle members, or the like, at the corners of the building to form a weather tight structure and are secured to the floor and to each other in any convenient manner to permit the walls to be easily erected or disassembled.

For the purpose of permitting a number of buildings 65 of this type to be assembled to provide a building of larger size, the buildings are constructed of the same width or length, so that one wall of two such buildings may be removed and the buildings placed with their open sides 70 together to form a structure having twice the space of a single building. In this manner a number of such build-

ings may be assembled and connected together to provide a structure of any desired size.

For the purpose of forming a strong and weather tight detachable connection between the buildings when assembled, the joint structure of the invention embodies a roof connector member 20 in the form of an elongated, channel-shaped member, adapted to be placed in a horizontal, upwardly opening position with the sides 22 thereof extending upwardly interiorly of the adjacent side portions 18 of the roofs 16 of two adjacent buildings, to form an upwardly opening trough or gutter 24 between the roofs.

The connector member 20 is formed at each end with outturned side flanges 26 and a downturned bottom flange 28 which has a centrally located slot 30 whose lower end is open.

Side connector elements 32 are also provided which are positioned vertically between the adjacent vertical margins of adjacent walls of the buildings and extend from the floor 14 to the roof connector member 20. Each of these side connector elements is formed with a longitudinal groove 34 along each side into which the edge of the adjacent wall is fitted, and has at its upper end an upwardly opening, central notch 36 into which the roof connector member 20 fits. The external face of the side connector element is also cut away as best seen at 38 in FIGURE 6 to receive the end flanges 26 and 28 of the roof connector element, so that these flanges lie flush with the outer face of the side connector element when the parts are assembled. Each side connector element is provided with an opening 40, through which a fastening element, such as a bolt 42 provided with a wing nut 44 may be extended through the slot 30.

The upper ends of the side connector elements 32 are bevelled at the corners as seen at 46 for wedging engagement with the internal bevelled faces 48 of blocks 50 positioned within the roofs 16 whereby the roofs will be wedgingly connected together when the parts are assembled as best seen in FIGURE 5.

The side connector elements and the adjacent walls may be releasably secured together by suitable means such as the hooks 52 pivotally carried by the walls and which hook over bolts 54 on the elements and having provided with wing nuts 56. At their lower ends the side connector elements may be coextensive with the walls of the buildings which may be interfitted with the floor 14 in any desired manner to permit the parts to be easily assembled and disassembled to provide a weathertight connection.

In assembling and connecting the buildings by the use of the joint structure of the invention, two of the buildings are erected by assembling three walls of each building on the floor thereof, the walls being secured together at the corners by suitable fastenings, such as bolts, not shown, and the buildings are then placed with the open sides in facing relation. The side connector elements 32 are then placed between the vertical margins of the adjacent side walls of the buildings and secured thereto by the hooks 52. With the side walls thus connected together by the side connector elements, the roof connector member 20 is then placed in position by inserting the channel in the upwardly opening end notches 36 of the side connector elements with the flanges 26 and 28 positioned in the external recesses 38 of the elements, the bolts 42 being extended through openings 40 and slots 30 to secure the roof connector member in place.

The roofs 16 are then placed in position over the upper edges of the walls, the skirt formed by the side portions of the roofs extending downwardly, exteriorly over the upper edges of the walls to form a weathertight structure. The side portions of the roofs will then also extend downwardly inside of the channel of the roof connector member and exteriorly of the end flanges 26 and 28 and exteriorly of the side connector elements 32, to completely enclose the upper marginal portions of the walls.

When the roofs are thus positioned on the walls the

bevelled faces 48 of the internal blocks 50 in the roofs will be in wedging engagement with the bevelled faces 46 on the upper ends of the side connector elements 32 to further hold the buildings connected together.

5 In disassembling the structure, the roofs may first be lifted off, the roof connector member 20 removed, the side connector elements 32 being thereafter disconnected and the walls detached. The walls may then be placed one upon another on the floors 14 to form stacks and the 10 remaining parts of the structures placed in the stacks. With the parts thus arranged the roofs may be lowered over the stacks to enclose the same and secure to the floors in any convenient manner to form compact assemblages ready for transportation.

15 It will thus be apparent that the invention provides a portable building which may be formed into a compact assemblage for transportation and which includes a joint structure by which any number of such buildings may be connected together to form structures of larger capacity.

20 The invention is disclosed herein in connection with a certain specific embodiment of the same, but it will be understood that this is intended by way of illustration only, and that various changes can be made in the construction and arrangement of the parts, within the spirit of the 25 invention and the scope of the appended claims.

Having thus clearly shown and described the invention, what is claimed as new and desired to be secured by Letters Patent is:

30 1. The combination with rectangular buildings placed in juxtaposed relation with the adjacent facing walls of the buildings removed to form a rectangular enclosure, each of said buildings having a demountable roof of inverted rectangular tray shape whose sides are positioned in external overlying relation to the upper marginal portions of the walls of the building, of means for connecting the buildings together comprising a connector member of channel shape located in an upwardly opening position with the sides of the channel disposed inwardly of the adjacent sides of the roofs and having outturned end flanges having edge portions positioned in abutting relation to the upper edge portions of adjacent walls of the buildings and vertically extending connector elements positioned in overlapping relation to adjacent side margins of said adjacent side walls and said end flanges.

45 2. The combination with rectangular buildings placed in juxtaposed relation with the adjacent facing walls of the buildings removed to form a rectangular enclosure, each of said buildings having a demountable roof of inverted rectangular tray shape whose sides are positioned

50 in external overlying relation to the upper marginal portions of the walls of the building, of means for connecting the buildings together comprising a connector member of channel shape located in an upwardly opening position with the sides of the channel disposed inwardly of the adjacent sides of the roofs and having outturned end flanges having edge portions positioned in abutting relation to the upper edge portions of adjacent walls of the buildings and also having downturned end flanges, and vertically extending connector elements adapted to be 55 positioned in overlapping relation to adjacent side margins of said adjacent side walls and said flanges.

60 3. The combination with rectangular buildings placed in juxtaposed relation with the adjacent facing walls of the buildings removed to form a rectangular enclosure, each of said buildings having a demountable roof of inverted rectangular tray shape whose sides are positioned in external overlying relation to the upper marginal portions of the walls of the building, of means for connecting the buildings together comprising a connector member of channel shape located in an upwardly opening position with the sides of the channel disposed inwardly of the adjacent sides of the roofs and having outturned end flanges having edge portions positioned in abutting relation to the upper edge portions of adjacent walls of the

65 buildings and also having downturned end flanges, and 70 vertically extending connector elements adapted to be positioned in overlapping relation to adjacent side margins of said adjacent side walls and said flanges.

75

vertically extending connector elements positioned in overlapping relation to adjacent side margins of said adjacent side walls and said flanges, each of said connector elements having an upper end notch shaped to fit exteriorly over the bottom and sides of said connector member.

4. The combination with rectangular buildings placed in juxtaposed relation with the adjacent facing walls of the buildings removed to form a rectangular enclosure, each of said buildings having a demountable roof of inverted rectangular tray shape whose sides are positioned in external overlying relation to the upper marginal portions of the walls of the building, of means for connecting the buildings together comprising a connector member of channel shape located in an upwardly opening position with the sides of the channel disposed inwardly of the adjacent sides of the roofs and having outturned end flanges having edge portions positioned in abutting relation to the upper edge portions of adjacent walls of the buildings and also having downturned end flanges, 20

and vertically extending connector elements positioned in overlapping relation to adjacent side margins of said adjacent side walls and said flanges, each of said connector elements having an upper end portion which is cut away to fit exteriorly over the bottom and sides of said connector, the inner faces of said flanges being positioned in contact with the outer faces of the connector elements.
